UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

BROACHING ATTACHMENT FOR ROCK DRILLS.

Application filed November 11, 1925. Serial No. 68,362.

This invention relates to rock drills, but more particularly to a broaching attachment for fluid actuated rock drills of the hammer type.

5 In quarrying slate, granite or similar rock formation, it is a common practice to remove the rock in the form of rectangular blocks. A convenient and practical method of severing such blocks from the mass is to drill 10 a line of holes, leaving a narrow wall of material between adjacent holes. The walls thus formed are then cut away by means of a broach. This method of quarrying symmetrical blocks of rock has been found to 15 be considerably more economical than it would be to form a cut with an ordinary drill steel. However, with the front heads heretofore used for broaching operations it has been exceedingly difficult to prevent the 20 broach from creeping away from the narrower section of the wall between the holes to the wider part. This obviously requires the removal of a greater amount of material and consequently increases the operating 25 costs.

It is accordingly an object of this invention to enable a broaching tool to be rigidly guided and held against any tendency to depart from a desired course.

30 Another object is to construct a broaching attachment which may be quickly substituted for an ordinary rock drill front head and which will permit quick removal of the broaching tool from the attachment.

35 Further objects will be in part obvious and in part pointed out hereinafter.

The invention consists of the combinations of elements, features of construction and arrangement of parts having the general 40 mode of operation substantially as herein-after described and more particularly pointed out in the appended claims and illustrated in the accompanying drawings, in which

Figure 1 is an elevation of the front end 45 of a rock drill equipped with an attachment constructed in accordance with the invention with the guiding block removed in illustrating one of its uses,

Figure 2 is an elevation partly in section taken through Figure 1 on the line 2—2 looking in the direction of the arrows,

Figure 3 is a perspective view illustrating the manner in which the guide block may be removed from the attachment for the purpose of removing the broaching tool, and

Figure 4 is a transverse sectional view taken through Figure 2 on the line 4—4 looking in the direction of the arrows.

Referring to the drawings, the invention is shown embodied in a rock drill of which 60 only a front portion of a cylinder A is shown. Within the cylinder A is a bushing B which acts as a guide for a hammer piston C adapted to reciprocate therein to deliver blows to an anvil block D.

65 In accordance with the present invention, an attachment or a front head E is supported by the cylinder A and preferably secured thereto by means of a pair of cushioned side bolts F which extend through 70 lugs G and H of the cylinder A and the front head E respectively. The bolts F are provided with springs J which serve to hold the front head E yieldably within the cylinder A. Nuts K screwed on the ends of 75 the bolts F provide a seat for one end of the springs J and also serve as a means for adjusting the tension of said springs.

The front head E in this instance has a 80 forwardly projecting cylindrical portion L to which is preferably secured integrally an extension O provided on its inner face P with a flat cheek plate Q having a plane surface which in this instance serves as a guide for one face of a broaching tool R. The 85 cheek plate Q is preferably somewhat shorter than the face P so that a shoulder S is thus formed against which a face T of a head U formed on the broaching tool R may 90 strike. Secured removably to the extension 95 O is a guide block V having a recess W on its inner side. The recess W is of substantially the same width as the broaching tool R and cooperates with edges X of the tool R for preventing lateral movement of said 100 tool. The depth of the recess W is preferably equal to the combined thickness of the tool R and the cheek plate Q so that the sides of the recess will also closely engage the sides of the cheek plate Q and thus 105 serve to prevent lateral movement of the guide block V with respect to the extension O. At the inner end of the recess W is formed a shoulder Y similar to the shoulder S on the extension O and adapted to be in line therewith when the guide block V is secured in position on the extension O.

In this way the head U of the broaching tool R may impact equally against both shoulders. A space Z formed by the shoulders S 110

and Y provides a path for the head U of the broaching tool so that it may extend freely into the path of the anvil block D to receive the blows transmitted by said anvil block from the piston C.

Convenient means are provided for quickly securing the guide block V to the extension O. To this end the extension O is provided with slots b at its sides to receive eye-bolts c which in this instance are pivoted on pins d arranged through the extension O. Suitable slots e are likewise formed in the guide block V to receive the eye-bolts c. Nuts f are in this instance screwed on the ends of the eye-bolts c for the purpose of clamping the guide block V firmly in position.

The cutting face g of the broaching tool R is preferably concave and is of sufficient length to extend well on opposite sides of a wall h formed by the drill holes j in the rock k. The cutting face g of the broaching tool R is preferably of only slightly greater thickness than the narrowest portion of the wall h so that only a minimum amount of material will have to be removed between the holes j.

The advantages of this invention reside chiefly in the fact that that end of the broaching tool R which extends into the front head may be of equal cross sectional area as that portion of the tool exterior of the front head. In this way a high degree of rigidity may be obtained in the broaching tool and the tendency of the broaching tool to creep or depart from the desired line is eliminated.

I claim:

1. In a broaching attachment for fluid actuated rock drills of the hammer type having a cylinder and a reciprocatory hammer piston in the cylinder, the combination of a front head adapted to be secured to the cylinder and having an extension, a cheek plate on the extension forming a plane guiding surface, and means engaging the

cheek plate to cooperate with said plane surface of the extension for guiding a broaching tool.

2. In a broaching attachment for fluid actuated rock drills of the hammer type having a cylinder and a reciprocatory hammer piston in the cylinder, the combination of a front head adapted to be secured to the cylinder and having an extension formed with a plane guiding surface, a shoulder at one end of the guiding surface, removable means cooperating with the guiding surface of said extension to form a guide for a broaching tool, and a shoulder on the said means to lie in the same transverse plane as the shoulder on the guiding surface for retaining such broaching tool in the attachment.

3. In a broaching attachment for fluid actuated rock drills of the hammer type having a cylinder and a reciprocatory hammer piston in the cylinder, the combination of a front head adapted to be secured to the cylinder and having an extension provided with a plane surface, a recessed guide block removably secured to the extension and cooperating with said plane surface of the extension for guiding a broaching tool, and means for clamping said guide block to the extension.

4. In a broaching attachment for fluid actuated rock drills of the hammer type having a cylinder and a reciprocatory hammer piston in the cylinder, the combination of a front head adapted to be secured to the cylinder, an extension on the front head having a plane cheek plate forming one side of a guideway, a removable guide block having a recess to receive and guide a broaching tool, said recess cooperating with the cheek plate for preventing lateral movement of the guide block, and means for clamping the guide block in position.

In testimony whereof I have signed this specification.

CHARLES C. HANSEN.
